BUILDING BLOCK

Russell P. Hester, Chelsea, Okla.

Application September 5, 1946, Serial No. 634,506

2 Claims. (Cl. 72—41)

1

This invention relates to concrete building blocks.

An object of this invention is to provide an improved building block which includes a depending locking tongue at one or both ends for engagement with a lower or succeeding block.

Another object of this invention is to provide a building block wherein end abutting blocks are formed with complementary tongues extending into a central chamber formed in a lower block, and the confronting end walls of horizontally aligned blocks are so arranged and constructed as to provide a chamber to receive binder cement to thereby bind the blocks together in horizontal series.

A further object of this invention is to provide a concrete building block which is formed with an inclined outer side and a lower depending flange for overlapping engagement with the upper outer edge of a lower block to thereby eliminate capillary movement of moisture through the joints between superposed blocks.

With the above and other objects in view, my invention consists in the arrangement, combination and details of construction disclosed in the drawings and specification, and then more particularly pointed out in the appended claims.

In the drawings.

Figure 1 is a perspective view, partly broken away and in section, of a wall constructed from concrete blocks embodying this invention.

Figure 2 is a perspective view of an opening forming block.

Figure 3 is a perspective view of one of the wall forming blocks.

Figure 4 is a fragmentary perspective view, partly in section, showing the use of the opening forming blocks.

Figure 5 is an end elevation of a wall formed with blocks embodying this invention.

Figure 6 is a fragmentary vertical section showing the joints between the abutting ends of these blocks.

Figure 7 is a perspective view of one of the inner corner forming blocks.

Figure 8 is a detail front elevation, partly broken away, and in section, of the block shown in Figure 7.

Referring to the drawings, the numeral 10 designates generally a rectangularly shaped block which is formed of inner and outer walls 11 and 12. The walls 11 and 12 are connected together by means of end walls 13 and 14 which are spaced inwardly from the adjacent vertical edges of the inner and outer walls so as to thereby form frag-

2

mentary chambers 15 and 16 to receive the binder cement. Where the blocks 10 are disposed in end abutting relation the abutting block will also have a complementary binder cement chamber for receiving the binder cement so that the end edges of the inner and outer walls of the block may be disposed in abutting relation.

The block 10 also includes a pair of intermediate transverse walls 18, 19, forming a chamber 20 therebetween. The block 10, as shown in Figure 3, includes a depending lip or locking member 21 which is adapted to engage a portion of the chamber 20 of a lower block. The outer sides of conforming lips are adapted to be disposed as shown in Figure 6, in confronting and contacting relation so as to close the lower end of the combined chamber formed by the confronting ends of abutting blocks. The binder cement 22 is then inserted in the combined chamber so as to thereby firmly secure and seal the ends of adjacent blocks together.

The lips 21 are substantially one-half the width of the chamber 20 so that when two blocks are disposed in abutting relation, the upper end of the chamber 20 will be closed by these lips and the walls 18, 19 will lock the blocks together against lengthwise movement. The outer side or surface 23 of the outer wall 12 is inclined to the vertical, being inclined downwardly and outwardly, and the outer wall terminates at its lower end in a depending flange 24. The flange 24 is adapted to overlap the upper end of a lower block so as to prevent the entrance of water in the joint between superposed blocks, and also eliminate the passage of water by capillary attraction.

As shown in Figure 1, the concrete block 10c may be used for outer corners by forming the outer surface of one end wall on an inclination to the vertical as shown in 25, and the outer surface of the other wall also on an inclination to the vertical as shown at 26, and also forming a depending flange 26 for the overlapping engagement with the upper end of a lower block, with the opposite end of the block to be made so as to form a chamber 15c. The outside corner block also has a pair of intermediate transverse walls 18c and 19c to receive the depending lips of superimposed blocks, as shown in Figure 6.

Where the block is used for an inner corner, the wall 12 is formed with a vertical outer surface 27 for substantially one-half the length of the outer wall, as shown in Figure 7. The abutting end of a block 10, having a chamber 16, is adapted to engage against the flat vertical side surface 27 of the inside corner block, and cement

or other binder material may be poured into the chamber 16. The inside corner block, which is designated 10a, is also formed with a pair of intermediate transverse walls 18a and 19a to receive the depending lips of superposed blocks as shown in Figure 6. The lowermost block 10b which is adapted to engage on the upper surface of the foundation 28, has the locking lips 21 thereof removed or eliminated so that the blocks 10b will rest flat on the upper surface of the foundation 28.

The outer surface of the block 10b is inclined to the vertical, being inclined downwardly and outwardly as indicated at 29, and a depending flange 30 is formed integral with the outer wall 12b of the block 10b and is adapted to overlap the upper outer corner of the foundation 28.

In order to provide for the formation of openings in a wall which is being formed by these blocks, such as window or door openings, I have provided a rectangular block 31. This block 31 includes inner and outer walls 32, 33, the outer wall 33 having a depending outer flange 34 for overlapping engagement with the upper end of a lower block. The block 31 also includes one end wall 35 disposed inwardly from adjacent vertical edges of the inner and outer walls 32, 33, and also includes a second end wall 36. The wall 36 is formed with an opening or recess 37 for receiving an anchoring block 38.

The outer wall 33 is also formed with an end flange 39 so that the inner portion of the block 31 may overlap a vertically opening frame piece 40 as shown in Figure 4. The frame piece 40 is adapted to be nailed or otherwise secured to the inset blocks 38 which engage in the recesses or openings 37. The superposed blocks may be bolted together by means of an elongated bar 41, as shown in Figure 5. The lower end of the bar 41 is formed with a substantially right angular anchoring member 42 which is embedded in the foundation 28. The bar 42 extends upwardly in the space between one intermediate wall and an end wall, and a clamping nut 43 is threaded on the upper end of the rod 41 and bears against a washer 44 which engages on the upper side of a plate 45.

With a concrete block construction as hereinbefore described, the outer wall of each block is formed with a relatively smooth surface, and as superposed blocks overlap each other there is formed a lapped appearance on the outer side of the wall. These blocks may be disposed with their ends in abutting relation so that the joint between the blocks will be substantially concealed. Furthermore, the cement or binder which is disposed between superposed tiers of blocks will be concealed or covered by the overlapping lower flanges of the upper blocks so that moisture cannot enter the joint through the binder material.

I do not mean to confine myself to the exact details of construction herein disclosed, but claim all variations falling within the purview of the appended claims.

What I claim is:

1. A concrete building block comprising upstanding inner and outer walls, opposite end walls extending from the top edge to the bottom edge of said inner and outer walls and spaced inwardly from the end edges thereof connecting said inner and outer walls together, a pair of spaced apart intermediate walls between said inner and outer walls and extending to the top edge thereof, a lip depending from the bottom edge of each of said end walls and extending below the bottom edge of said inner and outer walls, said lip being substantially the width of one-half the distance between said spaced apart intermediate walls, whereby the lips of adjacent blocks may be locked in the space between the spaced apart intermediate walls of the block below, and the outer side of said lips being coplanar with said end edges whereby the outer sides of the lips of adjacent blocks will be in substantial contact for closing the lower end of the chamber formed between the adjacent inwardly spaced end walls.

2. A concrete building block comprising inner and outer walls, opposite end walls extending from the top edge to the bottom edge thereof and spaced inwardly from the end edges thereof connecting said inner and outer walls, a pair of spaced apart intermediate walls on opposite sides of the longitudinal median of said block between said inner and outer walls and extending to the top edge thereof, a lip depending from the bottom edge of each of said end walls and extending below the bottom edge of said inner and outer walls, the width of said lip being substantially one-half the distance between said spaced apart intermediate walls and the outer side of said lips being coplanar with said end edges whereby the depending lips of adjacent blocks may be locked in the space between the intermediate walls of the block below and whereby the outer sides of the said lips will be in substantial contact for closing the lower end of the chamber formed between the adjacent inwardly spaced end walls.
